US0D1109511S

(12) United States Design Patent (10) Patent No.: US D1,109,511 S
(45) Date of Patent: * Jan. 20, 2026

(54) MULE

(71) Applicant: Birkenstock IP GmbH, Linz am Rhein (DE)

(72) Inventor: Olaf Jantzon, Paris (FR)

(73) Assignee: BIRKENSTOCK IP GMBH, Linz am Rhein (DE)

() Term: 15 Years

(21) Appl. No.: 30/003,267

(22) Filed: May 12, 2025

Related U.S. Application Data

(62) Division of application No. 35/521,730, filed on Jul. 10, 2024 (U.S. filing date under 35 U.S.C. 384), and having an international filing date of Jul. 10, 2024.

(57) CLAIM

The ornamental design for a mule as shown and described.

DESCRIPTION

FIG. 1 is a front perspective view of the mule showing my new design;

FIG. 2 is a left side view thereof;

FIG. 3 is a top view thereof;

FIG. 4 is a right side view thereof;

FIG. 5 is a rear side view thereof;

FIG. 6 is a bottom view thereof; and,

FIG. 7 is a front view thereof.

The broken lines showing the sole of the mule form no part of the claim.

1 Claim, 7 Drawing Sheets
